UNITED STATES PATENT OFFICE

2,346,246

SEWING AND CEMENTING MACHINE

Fred Ashworth, Wenham, Mass., assignor to
United Shoe Machinery Corporation, Flemington, N. J., a corporation of New Jersey

Application February 13, 1941, Serial No. 378,764

12 Claims. (Cl. 112—43)

The present invention relates to sewing machines and more particularly to machines for attaching a welt strip by both stitches and cement along the edge of a shoe outsole.

If devices are applied to a sewing machine for performing cementing operations simultaneously with the sewing operations, difficulties often occur during the distribution of softened or fluid adhesive material employed in the cementing operations in preventing undesirable accumulations on the stitch forming devices or other portions of the machine. Also, unless special attention is given by the operator of the machine, the parts being sewed sometimes become stuck together in improper relationship before the sewing point in the machine is reached or a free portion of the sewing thread itself will come into contact with the fluid adhesive, causing the adhesive to be thrown in all directions by the whipping action of the thread during stitch formation. To overcome these difficulties, the usual practice is to apply adhesive as close as possible to the point of operation of the stitch forming devices in the machine, so that there is small opportunity for accumulations of adhesive on the machine or chance for the adhesive to come in contact with the thread before the sewing point is reached. As a further means of avoiding difficulty when cementing operations are performed simultaneously with the sewing, the adhesive may be applied to one or both of the parts to be sewed before presenting to the machine and allowed to become cured or otherwise rendered inactive. During sewing operations, the adhesive then is activated by heating or by applying a liquid activating agent. By so doing, application of the adhesive itself in a softened state and consequent misplacement of the adhesive is avoided.

Sewing machines usually are equipped with work clamping means, in the form of a work support and a presser foot, for compressing and holding the work for the stitch forming devices. If the activating liquid is applied too close to the operating point of the stitch forming devices, the adhesive will not have become sufficiently impregnated to form a secure bond between the parts on which the adhesive is used, the pressure of the clamping means being exerted too soon to compress the parts intimately together throughout the areas to be cemented.

Among the quickest acting adhesives in common use are those containing cellulose and employing a highly volatile and inflammable activating agent, such as acetone, ether, etc. Even with such adhesives, if the activating agent is applied

close to or at the operating point of a sewing machine according to previous cementing practices, complete activation does not occur in time for the clamping means to force the parts into intimate contact, so that full benefit of the adhesive in securing an effective cement bond is not obtained.

Accordingly, it is an object of the present invention to provide a novel and improved sewing machine in which the parts operated upon may be cemented with a secure bond throughout a substantial area while being sewn together, without in any way affecting adversely the sewing operations or requiring special attention on the part of the operator towards keeping accumulations of adhesive off the machine or preventing the parts operated upon from being prematurely stuck together. Other objects are to provide a simple and inexpensive attachment for shoe sewing machines for applying an activating liquid to the parts operated upon, which parts have been prepared with a layer of inactive adhesive, the arrangement being such that by the time the parts have reached the point of operation of the machine, the adhesive layer will have become sufficiently impregnated and softened to permit the adjacent surfaces to be brought intimately together with a secure cement bond simultaneously with the sewing operations.

It is within the scope of the present invention to cement two or more materials in any form or shape together while being operated upon in a sewing machine, the work clamping means of the machine acting not only to hold the work in proper relationship with the stitch forming devices of the machine, but also to exert a pressure to bring the parts into intimate contact; although in the illustrated embodiment of the invention, means is provided for applying activating liquid to an inactive layer of adhesive carried on a welt strip, said liquid applying means being located along the strip sufficiently in advance of the clamping means to permit the adhesive layer to become impregnated substantially to its full thickness in the time required for the welt to travel from the applying means to the clamping means at the normal sewing speed of the machine. With the type of cellulose containing adhesive referred to and with the usual volatile solvents employed with this adhesive, suitable impregnation requires three to five seconds and the liquid applying means is spaced sufficiently from the clamping means to provide this time interval. In the illustrated form of this feature, a tubular covering is employed for the adhesive covered

strip after passing the means for applying the activating liquid so that the liquid will not escape by evaporation or otherwise, particularly during those periods when the machine is at rest. With a covering for the activated adhesive, it is unnecessary to take special precautions in starting a seam to insure that the softening action of the activating liquid is not lost.

Further features of the invention relate to a simple and effective arrangement for adjusting the quantity and for regulating the distribution of activating liquid along the surface of the adhesive layer on the parts being sewn and to a mechanism for shutting off the flow of activating liquid when sewing operations are terminated.

These and other features of the invention consist in certain novel constructions, combinations and arrangements of parts hereinafter described and claimed, the advantages of which will be readily understood by those skilled in the art from the following description and from the accompanying drawings, in which Fig. 1 is a view in side elevation and in section of certain portions of a shoe sewing machine embodying the features of the invention; Fig. 2 is a sectional view of a shoe illustrating the arrangement of a welt strip which is sewed and cemented simultaneously on the machine of Fig. 1; Fig. 3 is a detail plan view on an enlarged scale of the work support and activating liquid applying attachment; and Fig. 4 is a sectional view on a still further enlarged scale of the liquid applying and spreading device illustrating its action on an adhesively coated welt strip.

The machine of the present invention is provided with means for directing a welt strip into a seam being sewn and to cement the strip securely in place simultaneously with the sewing operations. The machine is intended to operate on a shoe having an outsole previously attached, such as a cemented or stitchdown type of shoe in which one edge of the welt strip is pressed firmly into the crevice formed by the outturned margin of the upper between the bulging sides of the upper and the projecting margin of the outsole. Such a shoe is illustrated in Fig. 2 of the drawings and is composed of an upper 2 secured in lasted relationship with a canvas sheet 4 forming an insole or mid-sole for the shoe by an inseam 6 inserted on a machine disclosed in U. S. Letters Patent of Fredericksen, No. 2,246,993, of June 24, 1941. The lasted upper and mid-sole, after being sewn together on this machine, have their projecting marginal portions trimmed off close to the inseam and the resulting shoe has cemented to its tread surface an outsole 8 suitably shaped to provide a projecting marginal portion. The shoe with the outsole 8 thus attached is then operated upon by the present machine, simultaneously to sew and cement the welt strip, indicated at 10, to the projecting marginal portion of the outsole with the inner edge of the welt strip held securely in the crevice formed by the bulging upper and the outsole.

The machine illustrated in the drawings is a lockstitch outsole shoe sewing machine similar in construction and manner of operation to that disclosed in U. S. Letters Patent No. 1,169,909 of February 1, 1916, of the present inventor, and of the same inventor and another, No. 2,271,611 of February 3, 1942. Referring to Fig. 1, of the drawings, the machine has a curved hook needle 12, a rotary shuttle 14, a looper 16, a work support 18, a presser foot 20, and other stitch forming and thread handling devices operated by a

sewing shaft 22 and suitable mechanisms driven thereby. To start and stop the machine, there are provided treadle controlled driving and stopping mechanisms including a link 24, a lever 26 to which the link is connected, and a shaft 28 on which the lever is secured for raising the presser foot from the work support at the end of a seam and for performing other operations incident to the completion of the sewing operations. The work support 18 of the machine is provided with a welt guiding passage 30 adjacent to and in alignment with the point of operation of the stitch forming device through which the welt strip 10 is led to the sewing point and against the shoe at the sewing point between the work support and presser foot. To fit closely within the crevice formed by the bulging upper and projecting margin of the insole, the inner edge of the welt strip 10 is beveled somewhat so that when secured in close fitting relationship with the crevice, a tight joint is secured.

Before use of the welt strip 10, one side surface and the surface of the beveled edge is coated with a layer 31 of quick drying cellulose containing adhesive which is allowed to become at least partially cured before use. To cement the welt while sewing, this layer of adhesive is activated by thorough softening so that a secure bond will be formed with the outsole. The activating agent consists of a liquid including acetone, ether, alcohol, or other similar highly volatile and ordinarily combustible organic solvents, the welt being drawn towards the work support by the feeding action of the machine.

According to the present invention, the solvent is applied at a sufficient distance from the supporting surface of the work support and the point of operation of the stitch forming devices to insure thorough impregnation substantially throughout the thickness of the adhesive layer on the welt. Under the clamping pressure of the presser foot, the adhesive is then forced throughout the width of the welt into the pores of the outsole to which it is being sewed and the parts are pressed into intimate contact. By thoroughly impregnating the layer of adhesive to a substantial depth, full benefit of the clamping pressure of the presser foot on the resulting bond is obtained so that after the parts leave the point of operation of the machine and the adhesive hardened, they are securely cemented as well as attached by stitches.

To apply the activating liquid a sufficient distance away from the point of sewing and clamping operations, the welt strip 10 is led through slots adjacent the lower closed end wall of a cylindrical cartridge 32 through the upper open end of which the activating liquid is introduced. The cartridge 32 is slidably mounted on a sleeve 34 having inserted at its lower end a plug or pad of absorbent material 36. The upper end of the tube 34 has an internal thread engaging an external thread on a hollow terminal 38 for a tubular conductor 40, the upper end of which is connected to a flow controlling valve 42 secured to the machine frame. The conductor 40 is of sufficient rigidity to support the sleeve 34 and the cartridge 32 and to maintain them in proper relationship with the welt guide 30 as the welt is drawn towards the sewing point. The cartridge is located about four inches from the point of sewing operations and at this distance, it will take three to five seconds at the normal sewing speed of the machine for the welt to move from the cartridge to the work support. If a greater

separation is made, there is no particular benefit obtained and there is a possibility that the adhesive will be softened too much. If a shorter length of time for impregnation is given, the surface only of the adhesive layer will be activated and the pressure of the presser foot on the welt will not bring the parts operated upon into as intimate contact as desirable for this type of work.

As a means to prevent evaporation or other loss of activating liquid from the adhesive layer on the welt, the welt, during its travel from the cartridge 32 to the guide 38, is surrounded by a flat tubular covering 44 secured in heat conducting relation at one end to the work support in alignment with the guide 38. Due to the movements of the work support, which as in the machine of the Patent No. 2,271,611 referred to, cooperates with the presser foot to feed the work while clamped, the other end of the tubular covering 44 for the welt is spaced slightly from the cartridge so as not to disturb the position of the cartridge.

To distribute the activating agent evenly along the surface of the adhesive layer 34, the welt is pressed yielding against the lower projecting end of the absorbent pad 36 by a light spring 46 coiled about the sleeve 34 and compressed between a shoulder at the lower end of the sleeve and a threaded member 48 slidably mounted on the sleeve and engaging threads on the cartridge 32. The pressure exerted by the spring is applied to the welt through the closed lower end wall of the cartridge, forcing the welt against the exposed end of the pad.

As the absorbent pad drags along the layer of adhesive on the welt, it may become worn so as to require adjustment. Suitable adjustment is obtained in the position of the pad by rotating the sleeve 34 on the threaded terminal 38, thus forcing the pad through the lower end of the sleeve 34 the required amount. By enclosing the welt within the cartridge 32 at the location where the activating liquid is being applied, most of the loss of liquid by evaporation is eliminated and consequently, the hazard of fire is substantially reduced when inflammable activating liquid of the type referred to is employed. A particular advantage in this respect is obtained by the arrangement of the slots in the lower end of the cartridge and in the introduction of activating liquid through the upper end since there is no opportunity for the liquid to run down the cartridge and collect on extended areas or other parts of the machine, thus decreasing substantially the exposed wetted surfaces from which evaporation may take place. Also, the sewing thread is kept by the covering 44 from accidental contact with activated adhesive until the sewing point is reached.

The supply of activating liquid is contained in a reservoir 50 mounted at the top of the machine frame, and is led to the valve through a piped connection 52. To control the flow of liquid to the cartridge 32, the valve 54 is constructed with a needle-pointed spring-pressed plunger 56 and an adjusting thumb nut 58 of well-known form to raise and lower the plunger 56 from its seat in the valve. The valve in the position shown in Fig. 3 is closed, shutting off the flow of liquid, and when sewing operations are started, the rod 24 of the stopping mechanism is moved forwardly until an adjustable set screw 58 threaded in a bracket 60 on the rod presses a flipper 62 pivoted

to the outer end of the plunger 54 of the valve. Movement of the flipper about its pivot on the plunger causes a cam portion on the flipper, which engages the thumb nut 58, to raise the plunger from its seat an amount determined by the position of the thumb nut. To locate the flipper in proper position when the valve is closed, the valve is provided with a buffer spring 64 having a projection 66 engaging a roughened surface of the thumb nut 58 and an end extending into the path of movement of the flipper. The flipper, when contacting the spring, is held properly to be engaged by the set screw 58 as the machine is started.

Sewing machines of the type above identified ordinarily are heated to facilitate handling wax coated sewing threads. A number of electrical heating units are provided in the machine frame for this purpose, one of which for the shuttle is indicated at 68 in Fig. 1. The heat in the machine, therefore, is conducted from the work support to the tubular covering 44 which, in the illustrated construction, is composed of copper, to conduct the heat rapidly. The amount of heat conducted by the tubular covering ordinarily is sufficient to volatilize some of the activating liquid, improving its penetrating effect on the adhesive as the welt is drawn within the tubular covering. The cartridge 32 being separated from the end of the covering 44 by a short gap, is not heated by conduction and as a result, the liquid is distributed evenly over the adhesive layer before being drawn into the covering.

The nature and scope of the invention having been indicated, and a construction embodying the several features of the invention having been specifically described, what is claimed is:

1. A machine for simultaneously sewing and cementing a welt strip carrying a layer of inactive quick drying adhesive containing cellulose to the margin of a shoe outsole, in which a highly volatile activating liquid is employed having, in combination, stitch forming devices, work clamping means, a guide for directing a welt strip towards the point of operation of the stitch forming devices, a supply of activating liquid, activating liquid applying means located sufficiently in advance of the clamping means to provide a time interval within which the adhesive layer may become impregnated to a substantial depth while the welt is traveling from the liquid applying means to the clamping means at the normal sewing speed of the machine, and means to prevent escape of liquid evaporated from the adhesive before reaching the clamping means.
2. A machine for simultaneously sewing and cementing a welt strip carrying a layer of inactive adhesive to the margin of a shoe outsole, in which a highly volatile activating liquid is employed having, in combination, stitch forming devices, work clamping means, a guide for directing a welt strip towards the point of operation of the stitch forming devices, a supply of activating liquid, activating liquid applying means located sufficiently in advance of the clamping means to provide a time interval within which the adhesive layer may become impregnated to a substantial depth while the welt is traveling from the liquid applying means to the clamping means at the normal sewing speed of the machine, and a tubular covering for the welt between the activating liquid applying means and the clamping means to prevent escape of liquid.

evaporated from the adhesive and to conduct heat from the machine to the adhesive on the welt.

3. A machine for simultaneously sewing and cementing a welt strip carrying a layer of inactive adhesive to the margin of a shoe outsole, in which a highly volatile activating liquid is employed having, in combination, stitch forming devices, work clamping means, a guide for directing a welt strip towards the point of operation of the stitch forming devices, a supply of activating liquid, a cartridge having slots in its side walls at its lower end through which the welt strip is guided to apply the activating liquid to the adhesive layer sufficiently in advance of the clamping means to cause the layer to become impregnated substantially to its full thickness before reaching the clamping means, and an absorbent pad in the cartridge for distributing the activating liquid evenly along the surface of the inactive adhesive as the welt passes through the slots in the cartridge.

4. A machine for simultaneously sewing and cementing a welt strip carrying a layer of inactive adhesive to the margin of a shoe outsole, in which an activating liquid is employed having, in combination, stitch forming devices, work clamping means, a guide for directing a welt strip towards the point of operation of the stitch forming devices, a supply of activating liquid, a cartridge having slots in its side walls through which the welt strip is guided to apply the activating liquid to the adhesive layer sufficiently in advance of the clamping means to cause the layer to become impregnated substantially to its full thickness before reaching the clamping means, an absorbent pad in the cartridge for distributing the activating liquid along the surface of the inactive adhesive as the welt passes through the slots in the cartridge, and means in the cartridge for pressing the welt strip yieldingly against the pad.

5. A machine for simultaneously sewing and cementing a welt strip carrying a layer of inactive adhesive to the margin of a shoe outsole, in which a highly volatile activating liquid is employed having, in combination, stitch forming devices, work clamping means, a guide for directing a welt strip towards the point of operation of the stitch forming devices, a supply of activating liquid, a conductor for bringing the activating liquid towards the welt strip, means at the end of the conductor for distributing the liquid over the adhesive layer, and a hollow slotted cartridge through the lower end of which the welt strip passes enclosing the distributing means to reduce evaporation of the liquid at the point of application.

6. A machine for simultaneously sewing and cementing a welt strip carrying a layer of inactive adhesive to the margin of a shoe outsole, in which an activating liquid is employed having, in combination, stitch forming devices, work clamping means, a guide for directing a welt strip towards the point of operation of the stitch forming devices, a supply of activating liquid, a conductor for bringing the activating liquid to the welt strip, means at the end of the conductor for distributing the liquid over the adhesive layer, a hollow slotted cartridge through which the welt passes enclosing the distributing means to reduce evaporation of the liquid at the point of application, and a spring inside the cartridge for pressing the slotted end of the cartridge towards the distributing means.

7. A machine for simultaneously sewing and cementing a welt strip carrying a layer of inactive adhesive to the margin of a shoe outsole, in which an activating liquid is employed having, in combination, stitch forming devices, work clamping means, a guide for directing a welt strip towards the point of operation of the stitch forming devices, a supply of activating liquid, a conductor for bringing activating liquid towards the welt strip, a threaded terminal at the end of the conductor, an adjustable threaded sleeve surrounding the terminal, an absorbent pad in one end of the sleeve to engage the end of the terminal and arranged to be forced out of the end of the sleeve by engagement with the end of the terminal, and means for yieldingly pressing the adhesive layer on the welt strip against the pad during its passage towards the stitch forming devices of the machine.
8. A machine for simultaneously sewing and cementing a welt strip carrying a layer of inactive adhesive to the margin of a shoe outsole, in which an activating liquid is employed having, in combination, stitch forming devices, work clamping means, a guide for directing a welt strip towards the point of operation of the stitch forming devices, a supply of activating liquid, a conductor for bringing activating liquid towards the welt strip, a threaded terminal at the end of the conductor, an adjustable threaded sleeve surrounding the terminal, an absorbent pad in one end of the sleeve to engage the end of the terminal and arranged to be forced out of the end of the sleeve by engagement with the end of the terminal, a hollow slotted cartridge slidably mounted on the sleeve and formed with a closed end wall adjacent the end of the sleeve, and yielding means for pressing the closed end wall of the cartridge towards the end of the sleeve to cause the projecting absorbent pad to wipe along the adhesive layer as the welt is drawn through the slots in the cartridge.
9. A machine for simultaneously sewing and cementing a welt strip carrying a layer of inactive adhesive to the margin of a shoe outsole, in which an activating liquid is employed having, in combination, stitch forming devices, work clamping means, a guide for directing a welt strip towards the point of operation of the stitch forming devices, a supply of activating liquid, a conductor for bringing the activating liquid towards the welt strip, means at the end of the conductor for distributing the liquid over the adhesive layer, a hollow slotted cartridge through which the welt strip passes enclosing the distributing means to reduce evaporation of the liquid at the point of application, and a valve actuated by the machine to shut off the supply of activating liquid from the conductor when the sewing operations are terminated.
10. A machine for simultaneously sewing and cementing a welt strip carrying a layer of inactive adhesive to the margin of a shoe outsole, in which an activating liquid is employed having, in combination, stitch forming devices, work clamping means, a guide for directing a welt strip towards the point of operation of the stitch forming devices, a supply of activating liquid, a conductor for bringing the activating liquid towards the welt strip, means at the end of the conductor for distributing the liquid over the adhesive layer, a hollow slotted cartridge through which the welt strip passes enclosing the distributing means to reduce evaporation of the liquid at the point of application, and an adjustable valve for regulat-

ing the flow of activating liquid during sewing and for shutting off the flow of liquid when the sewing operations are terminated.

11. A machine for simultaneously sewing and cementing a welt strip carrying a layer of inactive adhesive to the margin of a shoe outsole in which a volatile activating liquid is employed having, in combination, stitch forming devices, means for heating the stitch forming devices, work clamping means, a guide for directing a welt strip towards the point of operation of the stitch forming devices, a supply of activating liquid, a metallic tubular covering for the welt before entering the welt guide arranged in heat conducting contact with heated portions of the machine to volatilize, at least in part, activating liquid drawn into the covering with the welt, and means arranged in spaced relation to the covering for applying the activating liquid to the adhesive layer on the strip sufficiently in advance of the clamping means to cause the layer to become impregnated in the time taken for the welt to travel through the tubular covering.

12. A machine for simultaneously sewing and cementing a welt strip carrying a layer of inactive quick drying adhesive containing cellulose to the margin of a shoe outsole in which a highly volatile organic activating liquid is employed having, in combination, stitch forming devices, a guide adjacent to the point of operation of the stitch forming devices for directing the welt strip against the shoe, work clamping means at the 10 sewing point formed to compress the welt strip throughout its width against the shoe, a supply of activating liquid, and activating liquid applying means located sufficiently in advance of the welt guide and clamping means to provide a time 15 interval of from three to five seconds within which the adhesive layer may become impregnated to a substantial depth while the welt is traveling from the liquid applying means to the clamping means at the normal sewing speed of the machine.

FRED ASHWORTH.
